UNITED STATES PATENT OFFICE

HANS A. HOLMBERG, OF DENVER, COLORADO

ROCK DRILLING MACHINE

Application filed November 30, 1927. Serial No. 236,626.

My invention relates to rock drilling machines, and has for its principal object the provision of a rock drill which requires no auxiliary apparatus, such as an air compressor or the like, for its operation.

Another object of my invention is to provide a rock drill that consumes very little power.

A further object is to provide a rock drill which may be manually operated by one man when desired, the machine automatically holding, guiding, rotating and feeding the drill forward as the hole deepens as the man manually rotates the drive shaft.

A further object is to provide such a rock drill that is light in weight and easily portable.

A further object is to provide a rock drill which may be readily dismantled and folded into small compass for transport.

A further object is to provide a rock drill that permits easy removal and exchange of drill-bits.

A further object is to provide a rock drill having self-contained means for feeding water or air through the drill-bit to clear the hole of chips and dust.

Further objects and advantages appear in the details of construction, which is designed for efficiency, simplicity and economy.

In the drawings which are appended hereto and form a part of this specification, Figure 1 is an elevation of the left side of my improved rock drill, showing the hammer in striking position. Figure 2 is an elevation of the right side of my invention, showing the position of the hammer subsequent to striking the drill. Figure 3 is a section taken along the line 3—3 of Figure 2, except that the hammer is here shown in its lowermost position. Figure 4 is a top plan view through the reservoir and bit-holder. Figure 5 is a top plan view of the bit-rotating mechanism. Figure 6 is an enlarged section taken on the line 6—6 of Figure 10. Figure 7 is a section taken on the line 7—7 of Figure 4. Figure 8 is a section taken along the line 8—8 of Figure 2. Figure 9 is a section taken along the line 9—9 of Figure 8. Figure 10 is a section taken along the line 10—10 of Figure 8. And

Figure 11 is a section taken along the line 11—11 of Figure 8. Similar numerals indicate similar parts in all views.

My improved rock drill operates by swinging a heavy hammer in a spiral path about a rotating driving shaft, as indicated in dotted lines in Figures 1 and 2. This hammer strikes the drill-bit at a point on the greatest radius of said spiral path, as shown in Figure 1, then is automatically withdrawn to the smallest radius in order to clear said drill-bit, continue its rotation and accumulate momentum for another blow. The mechanism which guides the hammer in its spiral path deforms a part of my invention and is fully described herein, together with the means for rotating said driving shaft, rotating said drill-bit, feeding air or water through said drill-bit, automatically feeding said rock drill forward, enabling same to be quickly retracted and folded into compact form for transport.

The machine is fitted with the usual form of base 20, which may be fastened to a suitable support 21 by a clamp 22. Surmounting the base 20 is a guide shell 23, the sides of which are of channel section and within which is mounted a longitudinal feed screw 24. Two blocks 25 and 26 comprise the principal frame portion of the rock drill proper. These blocks are adapted to slide within the channel sections of the guide shell and are preferably supported on rollers which are herein shown on the top, side and bottom guiding surfaces of the blocks.

The blocks 25 and 26 are held in proper relation by the bars 27 and the tie-rods 28, making a rigid assembly which is longitudinally movable as a unit along the guide shell 23. An extension 29 is hinged at 30 to the upper end of the block 25, and normally maintained in an upright position, as shown, by the bars 27. The upper end of the extension 29 is T-shaped and supports a horizontal tubular member 31 by means of a hinge 32 and a shouldered stud 33, the smaller portion of which projects through a hole in the extension 29 and is retained by a pin 34.

The tubular member 31 is a combined support for the drill-bit and its rotating mecha-

nism, and reservoir for air or water, to be fed through said bit. Affixed to the body of the member 31 are front and rear end plates 35 and 36, respectively. An extension of the 5 front end plate 35 supports a chuck 37 which is bored to rotatably support the butt end of the drill-bit 38. An interior groove 39 in the forward portion of the chuck 37 engages a lug 40, formed on the bit 38, permitting free 10 rotation thereof but constraining it to follow the reciprocation of the chuck 37.

A retaining spring 41 covers the entering slot of the groove 39 to permit the insertion or withdrawal of the bit 38 from the chuck 15 37, but prevent its egress during operation of the machine. The bit 38 is of the usual hollow hexagon form except for the butt portion, which is formed cylindrically for rotation within the chuck 37. Surrounding the 20 rear end of the chuck 37 is an anvil or dolly 42, retained in position by a set screw. A passage 43 conveys water or air through the side walls of the dolly and chuck, terminating at its inner end in a nozzle 44 in alinement 25 with the central hole in the bit 38, and at its outer end in a connection for a flexible tube 45 which communicates with the interior of the member 31.

The bit 38 is further supported in the hub 30 of a ratchet wheel 46, which wheel is adapted to rotate within an extension of the front end plate 35 of the tubular member 31, and which wheel is held in place therein by a clip 46a. The hub of the ratchet 46 has a hexagonal 35 bore to fit the contour of the bit 38, with a longitudinal groove to permit the passage of the lug 40.

Movement is imparted to the ratchet 46 by a pawl 47 on a stem 48, adapted to reciprocate in a lug formed on the plate 35. The opposite end of the stem 48 is fitted with a roller 49, and a coil spring 50 acts to retract the pawl 47, which is advanced by the rearward movement of a transversely reciprocating cam 51 affixed to a stem 52. This stem is guided in a lug supported by the body portion of the member 31 and its outer end is circumferentially grooved for retention by means of a set screw in a socket formed in an 50 extended leg of a U-shaped mangle-rack 53, which is clearly illustrated in Figure 5.

The cam 51 is in the form of an unsymmetrical pyramid, as best shown in Figure 7, 55 each of its sides approaching the apex at a different angle. The stroke of the ratchet 46 can thus be varied by partially rotating the cam 51 about its axis and exposing a different face to the roller 49. A stem 54 extends rearwardly from the closed end of the mangle-rack 53 and is supported in a lug affixed to the tubular member 31. An arm 55 is fastened to the rearward end of this stem and extends transversely, terminating in a loop 60 65 for the engagement of a lug 56 which extends

downward from the chuck 37, and retained thereon by a pin 57.

The mangle-rack 53, together with the cam 51 and the arm 55, is reciprocated by the rotation of an intermittent pinion 58 in a well-known manner. The pinion 58 is keyed to the upper end of a vertical shaft 59, which is supported on the extension 29 of the front block 25.

Motion is transmitted to the vertical shaft 59 from a longitudinal shaft 60, through the bevel gears 61 and 62. The shaft 60 is supported in the front block 25 and in a bracket extending upward from the rear block 26, and has a bevel gear 63 keyed on its rearward end. The bevel gear 63 meshes with an intermittent bevel gear 64 mounted on a transverse driving shaft 65. The shaft 65 extends through and is supported in the rear block 26 and has a flange 66 formed on it adjacent the gear 64. Transverse teeth on this flange engage corresponding slots in the hub of the gear 64, causing it to rotate with the shaft 65. The shaft 65 extends beyond the gear 64, and carries adjacent the opposite end of the hub of said gear a washer 67, formed with transverse teeth on both faces and its periphery. These teeth engage slots in the hub of the gear 65, and in the hub of a radial stem 68, also mounted on the shaft 65, thus transmitting the motion of the shaft to said stem. Adjoining the outer end of the hub of the stem 68 is a washer 69, having two opposite teeth in its periphery only, and adjoining the outer face of this washer is a collar 70, pinned to the shaft 65, to retain the above-mentioned members in place.

Slidably mounted on the stem 68 is a sleeve 71a, forming a part of a hammer 71. Affixed to the inner end of the sleeve 71a is a collar 72, carrying a roller 73, which is adapted to engage the periphery of a stationary eccentric cam 74. This cam is supported on the hub of the gear 64 and by an extended arm 75 bolted to the block 26. Surrounding the sleeve 71a between the fixed collar 72 and a slideable collar 76 is a coil spring 77. The collar 76 is maintained at a fixed distance from the shaft 65 by means of the straps 78 and 79, the latter being forked to straddle the roller 73. The shaft or inner ends of these straps are yoked to surround the washers 67 and 69, having slots to engage the peripheral teeth of said washers.

Near the outer end of the stem 68 is a transverse slot 80, best shown in Figures 1 and 2. A latch 81, set into a recess in the head of the hammer 71 and pivoted on a pin 82, has a projecting end adapted to enter the slot 80 through an opening in the sleeve 71a. This latch is normally held in its engaged position by a spring 83, and its opposite end contacts a tappet 84, which protrudes through the striking face of the hammer 71, and is loosely retained by a transverse pin.

5 Mounted on the shaft 65 adjacent the right side of the block 26 is a two-lobed cam 85, fastened to the shaft by a through-pin 86, as illustrated in Figure 10. This cam acts on the enlarged head of a push rod 87, guided in a lug formed on the side of the block 26 and is pressed against the cam 85 by the springs 88. A latch 89 may be manually thrown to hold the push rod 87 out of engagement with the cam 85, and is held either in or out of engagement by a spring detent 90. A pawl 91 is pivoted in the lower end of the push rod 87 and adapted to actuate a ratchet 92, set in a recess in the block 26 and mounted on a sleeve 93 which loosely surrounds the feed screw 24. Movement of the ratchet 92 is transmitted to the sleeve 93 by transverse teeth formed on the forward side of said ratchet which engage slots in one end of an outer sleeve 94. Similar slots in the opposite end of the sleeve 94 and in the corresponding end of the sleeve 93 are engaged by keys formed in a collar 95, which is retained on the sleeve 93 by set screws, locking the assembly together. The sleeves 93 and 94 have bearing in the block 26 and project beyond the ends thereof.

30 The rearward projection of the sleeve 93 is enlarged and recessed to guide suitable extensions of two half-nuts 96 and 97, which are internally screw-threaded to engage the feed screw 24. When the half-nuts 96 and 97 are in their closed position, as shown in Figures 1, 2, 3 and 6, rotation of the sleeve 93 by the ratchet 92 and cam 85, acts through them to move the machine along the feed screw. When said half-nuts are in their open position, as shown in Figures 10 and 11, and indicated in dotted lines in Figure 6, the machine is disconnected from the feed screw 24 and may be moved freely along the guide shell 23.

45 A disc 98 having spiral grooves for the engagement of the extensions 99 and 100 of the half-nuts 96 and 97 is rotatably supported on the rearward extension of the sleeve 93, in position to be easily reached by the operator. As shown in solid lines in Figure 6, the extensions 99 and 100 are at the inner ends of their corresponding spiral grooves in the disc 98, and the half-nuts 96 and 97 are in their closed position.

55 A manual quarter turn clockwise of the disc 98 will bring the extensions 99 and 100 near the outer ends of the spiral grooves and spread the half-nuts 96 and 97 to their open position, clear of the thread on the feed-screw 24, as indicated in dotted lines in Figure 6. Reverse turn of the disc 98 will close the half nuts to their initial closed position.

60 Keyed to the shaft 65 adjacent the cam 85 is a spur pinion 101, whose function will be hereinafter explained. Beyond this pinion is a large spur gear 102, also keyed to the shaft 65. This gear meshes with a pinion 103

keyed to a counter shaft 104, mounted in bearings on the bars 27.

A spur gear 105, also keyed to the counter-shaft 104, meshes with a pinion 106, keyed to the shaft of an electric motor or other convenient source of power 107.

70 The countershaft 104 actuates a pump 108 by means of a crank and pitman. This pump feeds air or water as desired through a pipe 109 to the interior of the tubular member 31 at 110, where it is stored for conveyance through the hollow bit 38, to clear chips and dust from the hole being drilled. Both ends of the shaft 65 are squared for the application of a hand crank when desired, as indicated in dotted lines in Figure 3. Manual operation may be accelerated by removing the gear 102 and attaching an auxiliary crankshaft 111 carrying a gear 112, as indicated in dotted lines in Figures 1 and 2, which 80 meshes with the pinion 101. The shaft 111 is carried in a bracket 113, bolted to the block 26. By the use of this auxiliary shaft and gearing two or more revolutions of the shaft 65 per revolution of the hand crank 114 may 90 be obtained.

85 The cycle of operations of this rock drill is as follows: Beginning with the position shown in Figure 1, where the hammer 71 is about to strike the dolly 42. The shaft 65 is 95 continuously rotated, either by hand or power through the means described, and carries with it the hammer assembly, the intermittent gear 64 and the cam 85. As the hammer strikes the dolly, the tappet 84 is 100 depressed, releasing the latch 81 from the slot 80 in the stem 68. This action permits the spring 77 to expand, forcing the collar 72, sleeve 71a and hammer 71 inward toward the shaft 65 a sufficient distance so that the further rotation of the hammer 71 will be clear 105 of the dolly 42. The roller 73 now contacts the smallest radius of the eccentric cam 74 and continued rotation of the assembly acts to compress the spring 77 as the roller follows 110 the increasing radius of the cam, forcing the sleeve 71a and the hammer 71 to move in a correspondingly increasing radius and compressing the spring 77 between the collars 72 and 76. At the radius at which the hammer will align with the dolly 42, the slot 80 in the stem 68 aligns with the latch 81, the spring 83 causing engagement thereof. This movement of the latch also protrudes 115 the tappet 84, the hammer assembly thus being ready for another cycle of operations.

120 Rotation of the shaft 65 also brings the intermittent bevel gear 64 into mesh with the bevel gear 63 on the shaft 60, just subsequent to the blow of the hammer 71 on the dolly 42. 125 Motion is thus transmitted through the gears 64 and 63, the shaft 60, the gears 61 and 62, the shaft 59, and the intermittent pinion 58 to the mangle-rack 53. This gearing is so proportioned that the pinion 58 turns one 130

revolution clockwise during the engagement of the gears 64 and 63, and between blows of the hammer.

Figure 5 shows the pinion 58 and mangle-rack 53 as half way through their cycle of operations. The mangle-rack is in its rear-most position, the arm 55 having withdrawn the bit 38 from the bottom of the hole by means of the lug 56, chuck 42 and lug 40. At the same time, the bit has been partially rotated by the cam 51 acting on the roller 49 and advancing the pawl 47 and ratchet 46. The next half revolution of the pinion 58 will return the mangle-rack 57 to its forward position, advancing the bit 38 to the bottom and permitting the spring 50 to retract the pawl 47. Rotation of the cam 85 causes the push-rod 87 to make two strokes per revolution of the shaft 65, advancing the ratchet 92 through the pawl 91. This movement is transmitted to the half-nuts 96 and 97 through the sleeves 93 and 94, thus advancing the machine along the feed-screw 24 as the bit 38 penetrates the rock. If this feed is too rapid, the latch 89 may be thrown, holding the push-rod 87 away from the cam 85. If it is too slow, the operator may also advance the feed-screw by means of the ratchet handle 115, shown in Figures 1 and 2. When the bit has penetrated the rock the length of the feed-screw 24 and it becomes necessary to retract the machine to change bits, the disc 98 is given one-fourth turn clockwise, spreading the half-nuts 96 and 97 clear of the feed-screw and permitting rapid withdrawal of the machine.

To dismount the machine, the bars 27 are unbolted from the frame members 25 and 26, the pipe 109 is disconnected and the bars 27, motor 107, pump 108, and countershaft 104 are removed as a unit. The retaining pin 34 is then removed from the stud 33 and the tubular member 31, together with the bit-holding and rotating mechanism which it supports, are folded at the hinge 32 to lie parallel with the extension 29, which in turn is folded at the hinge 30 to occupy the space vacated by the removal of the bars 27. The clamp 22 may then be loosened and the base 20 removed therefrom, the machine being now in two relatively light and compact units.

I desire to have it understood that the specific form of my invention herein described and illustrated may be varied within the scope of the appended claims, without departing from the spirit thereof.

Having thus described my invention, I desire to secure by Letters Patent and claim:

1. In a rock drill the combination of a manually operated drive shaft mounted in suitable supports; a hammer rotatably mounted on said shaft; a drill bit mounted for intermittent rotation above said shaft;

means by the action of a pinion, rack, arm and chuck to draw said bit partially from said hole and force it back into said hole before and after each blow of said hammer; an intermittent gear drive for automatically advancing the drive shaft, hammer, and drill support as a unit along said support; means by fluid pressure being passed through said drill bit to clear the hole after each blow of the hammer; and means to withdraw said drive shaft, hammer, drill support and component parts from said work simultaneously when desired.

2. In a rock drill the combination of an adjustably mounted frame; bearing members carried in said frame; a drill support longitudinally movable in said frame a hollow drill carried in said support; a main shaft mounted transversely on said bearing members; a feed-screw carried in said frame; a feed-nut engaging said feed-screw means on said frame to move said drill support forward by intermittent rotation of said feed-nut; means operating with said screw whereby said support may be moved quickly away from said work; a hammer whose handle is secured on said main shaft and is rotatable therewith; means in said handle whereby said hammer may be retracted in its cycle after the blow has been struck to allow said hammer to pass the end of said drill; means to rotate said drill; means to introduce fluid pressure through a hollow in said drill to clear the hole being drilled; and means to rotate said main shaft as desired.

3. In a rock drill the combination of a drive shaft mounted in suitable supports; a hammer rotatably mounted on said shaft; a hollow drill bit mounted for intermittent rotation above said shaft; means to draw said bit partially from said hole and pass fluid pressure through said bit into said hole while the bit is drawn back; means to force the bit back into the hole before the next blow of the hammer; means to automatically advance the component parts of the drill along the support, a portion at a time, and to withdraw said mechanism from said work simultaneously when desired.

4. In a rock drill the combination of a rotatable hammer handle stem secured on a rotating shaft; another outer sliding sleeve surrounding said stem, having a hammer head on the end thereof; a dog pivoted in the hammer head means to collapse said sleeve and stem together by spring tension; a pin in the face of said hammer head adapted to be forced into said head when the head comes into contact with the drill and to release a dog engaged with said stem and sleeve, thereby releasing said sleeve from said stem; and means to draw said hammer and sleeve inwardly in the cycle of rotation and force it outwardly until the cycle is completed and another blow struck by the hammer.

5. In a rock drill the combination of a rotatable hammer secured on a sleeve handle; a handle stem carried within said sleeve and secured to a rotatable shaft; a spring mounted around said sleeve adapted when released to draw said hammer and sleeve inwardly in its cycle of rotation sufficient for the hammer to pass the head of the drill. 70

6. In a rock drill the combination of a manually-rotated drive shaft mounted in suitable support; a hammer rotatably mounted on said shaft; a drill bit mounted for intermittent rotation above said shaft in suitable bearings; means comprising a pinion, a rack and an arm attached to a drill bit chuck to draw said bit partially from said hole and force it back into said hole before and after each blow of said hammer; and an intermittent gear drive for automatically advancing the drive shaft, hammer, drill support as a unit along said support; and means to withdraw said drive shaft, hammer, and drill support as a unit from said work simultaneously when desired. 80

7. In a rock drill the combination of a rotatably mounted drive shaft; a hammer secured for rotation on said shaft; a drill bit mounted for intermittent rotation above said drive shaft and so situated that when the hammer is rotated the head will strike the rear end of the bit mounting; means to force fluids through said drill bit from a source of supply; a pump actuated by the rotation of said drive shaft to provide pressure for said fluid; means to intermittently advance said drive shaft upon its support by the action of intermittent gears; a screw and nut by which said drive shaft is advanced; means on said advance drive to release the action thereof and to discontinue the advance; and means to disassemble said device to provide a compact folding drill and support substantially as described. 90

8. In a rock drill the combination of a supporting frame; a screw in said frame to advance a rotatable shaft and its component parts along said frame; suitable bearings and framework upon which said drive shaft is mounted; a handle to rotate said screw as desired; a rotatable drive shaft mounted for rotation in suitable bearings; a ratchet wheel actuated by the rotation of said drive shaft adapted to rotate said screw; a motor mounted on said framework; intermeshing gears adapted to rotate said drive shaft from said motor; another drive shaft rotatable intermittently at right angles to said main drive shaft having intermeshing gears on the end thereof; another drive shaft at right angles thereto and driven by said gears; a mangle-rack rotated by an intermittent gear on the end of said last-mentioned shaft; a variable cam on the end of a drive shaft integral with said mangle-rack and adapted to move therewith; a roller adapted to contact with said cam and to move a pawl on the other end of a connecting shaft; a drill bit supported for rotation in suitable bearings; a chuck for holding said bit for rotation in a dolly; a ratchet for rotating said drill bit mounted therearound and to be actuated by said pawl; a fluid tank supported parallel with said drill bit; means to allow fluids to be forced from said tank through said drill bit to clear the hole being bored after each blow; a hammer stem mounted on said drive shaft; a hammer mounted on a sleeve surrounding said stem; a spring to draw said hammer inwardly in its cycle after the blow has been struck upon the chuck; a cam to actuate the hammer in its cycle; and means in the head of said hammer to release it so that the spring may actuate it in its cycle and draw it inwardly upon the stem to pass the chuck after the blow has been struck. 95

9. A drill comprising an adjustably mounted frame; bearing members carried in said frame; a drill support secured on said bearings and longitudinally movable on said frame; a drill carried in said support; a main drive shaft mounted on said bearing members; a ratchet to rotate said drill gears connecting said drive shaft with ratchet; and a hammer with its handle secured on and rotatable with said main shaft to strike said drill. 100

10. A drill comprising a frame having suitable bearings therein; a drill support mounted on and movable with said bearings; a hollow drill carried in said support; means to intermittently rotate said drill; a fluid chamber mounted parallel to said drill; means to force fluid from said chamber through said drill to clear out the hole being drilled; a shaft mounted in said bearings and at right angles to said frame; means to move said drill support and shaft in either direction on said frame; a hammer handle secured on and rotatable with said shaft; a hammer carried on said handle and adapted to strike the head of said drill when said shaft is rotated; and means to move said hammer on said handle immediately after each blow on the head of the drill, with other means to move the hammer relative to its handle in order to successively strike the head of the drill. 105

11. A drill comprising a frame, having a ball race therein; bearings carried in said race; a drill support mounted on and movable with said bearings; a drill carried in said support; means to intermittently rotate said drill; a shaft mounted in said bearings and at right angles to said frame; means to move said drill support and shaft in either direction on said frame; a hammer handle secured at one end on said shaft and rotatable therewith; a hammer carried on said handle; a plunger carried in said bore with one end protruding beyond the striking face 110

12. A drill comprising a frame, having a ball race therein; bearings carried in said race; a drill support mounted on and movable with said bearings; a drill carried in said support; means to intermittently rotate said drill; a shaft mounted in said bearings and at right angles to said frame; means to move said drill support and shaft in either direction on said frame; a hammer handle secured at one end on said shaft and rotatable therewith; a hammer carried on said handle; a plunger carried in said bore with one end protruding beyond the striking face 115

13. A drill comprising a frame, having a ball race therein; bearings carried in said race; a drill support mounted on and movable with said bearings; a drill carried in said support; means to intermittently rotate said drill; a shaft mounted in said bearings and at right angles to said frame; means to move said drill support and shaft in either direction on said frame; a hammer handle secured at one end on said shaft and rotatable therewith; a hammer carried on said handle; a plunger carried in said bore with one end protruding beyond the striking face 120

14. A drill comprising a frame, having a ball race therein; bearings carried in said race; a drill support mounted on and movable with said bearings; a drill carried in said support; means to intermittently rotate said drill; a shaft mounted in said bearings and at right angles to said frame; means to move said drill support and shaft in either direction on said frame; a hammer handle secured at one end on said shaft and rotatable therewith; a hammer carried on said handle; a plunger carried in said bore with one end protruding beyond the striking face 125

15. A drill comprising a frame, having a ball race therein; bearings carried in said race; a drill support mounted on and movable with said bearings; a drill carried in said support; means to intermittently rotate said drill; a shaft mounted in said bearings and at right angles to said frame; means to move said drill support and shaft in either direction on said frame; a hammer handle secured at one end on said shaft and rotatable therewith; a hammer carried on said handle; a plunger carried in said bore with one end protruding beyond the striking face 130

of the hammer and adapted to move a dog when said plunger is moved longitudinally in said bore; and means to move said hammer relative to its handle between each successive blow.

12. A drill of the class described comprising a rock drill; a main shaft mounted adjacent said drill; a handle having one end thereof secured on said shaft and carried 10 radially around said shaft when the shaft is rotated; a hammer carried on the free end portion of said handle to contact with the head of the said drill when the shaft is rotated; a sleeve integral with said hammer 15 and having a slot therein; a collar on the end of said sleeve; a spiral spring carried on said sleeve; a plunger carried in said hammer; means to release said hammer when said plunger contacts with said drill and 20 allows the tension of the spiral spring to expand, thus retracting said hammer and sleeve on said handle; and means to set said spiral spring as the handle and hammer are moved around said shaft by the rotation 25 thereof.

In testimony whereof I have affixed my signature.

HANS A. HOLMBERG.
